FIG. 6

UNITED STATES PATENT AND TRADEMARK OFFICE
CERTIFICATE OF CORRECTION

PATENT NO. : Des. 544,564 S
APPLICATION NO. : 29/237440
DATED : June 12, 2007
INVENTOR(S) : Richard E. Swan

Page 1 of 1

It is certified that error appears in the above-identified patent and that said Letters Patent is hereby corrected as shown below:

Title Page, Item (54) Title: the word "AND" should read --HAND--.

In the description, on the line beginning with the text "FIG. 6," the word "rear" should be deleted.

In the description, on the line beginning with the text "FIG. 7," the first occurrence of the words "and exploded" should be deleted.

Signed and Sealed this

Twenty-first Day of August, 2007

A handwritten signature in black ink, appearing to read "Jon W. Dudas", is centered within a rectangular box with a dotted background.
